UNITED STATES PATENT OFFICE.

GUSTAVE KAHN, OF DETROIT, MICHIGAN.

REINFORCED CONCRETE CONSTRUCTION.

1,085,428.

Specification of Letters Patent.

Patented Jan. 27, 1914.

Application filed August 29, 1912. Serial No. 717,687.

To all whom it may concern:

Be it known that I, GUSTAVE KAHN, a citizen of the United States, and a resident of Detroit, county of Wayne, and State of Michigan, have invented a new and Improved Reinforced Concrete Construction, of which the following is a specification.

This invention relates to structures of reinforced concrete, and its object is to provide a column and slab construction which shall require a minimum of concrete and a minimum of steel to sustain a given load on a predetermined area, and to provide reinforcing members for concrete floor construction which may be completely constructed at the factory at minimum cost.

This invention consists of a novel reinforcement for concrete structures and the combination thereof with concrete to form reinforced slabs, and comprises a series of radiating rods, preferably evenly spaced circumferentially, and means connecting their inner ends. These groups of rods may be employed to reinforce the concrete immediately around the columns of concrete structures and especially adapted to reinforce panels of concrete floors.

In the accompanying drawings, Figure 1 is a plan showing the manner in which the reinforcing members of the present invention may be arranged to reinforce a concrete structure. Fig. 2 is a portion of a vertical section through a floor panel on a somewhat larger scale. Fig. 3 is a plan showing the manner in which the reinforcements of this present invention may be placed in connection with a steel frame construction. Figs. 4 and 5 are vertical sections through the center of a panel, on a larger scale, showing two ways of forming the rods. Fig. 6 is another vertical section showing a slightly modified form of reinforcement.

In the carrying out of this invention, each of the members must be properly proportioned to meet the stress upon it, so that this description is prepared for engineers and others skilled in the art of concrete construction. It will be understood that the number and dimensions of the rods and the sizes of the connectors in each panel or column may be varied to suit each individual structure or portion of structure in which this invention is to be employed. The term "flat-slab" is intended to designate a floor structure which is regarded as a unit, extending between well defined boundaries,

and usually comprising a panel or a series of panels which have a continuous flat lower face, broken only by the supporting columns. Where the floor is entirely of reinforced concrete, the term will include such structures as are formed with integral beams formed in the floor itself, between adjacent columns, by means of proper reinforcing members.

This invention is clearly shown in the two plans, Figs. 1 and 3, of which Fig. 1 indicates a flat floor slab entirely formed of reinforced concrete and Fig. 3 shows the invention in combination with a steel frame. In Figs. 1 and 2, a series of vertical rods 1 are shown in the columns 2 in the usual manner. Flat floor slabs 3 extend between the columns, and rods 4, of any desired type, reinforce bands or zones of this concrete slab to form beams. Any other desired method 70 may be employed to reinforce the columns and to form these integral beams, as neither forms any part of this invention. As will be clearly seen, each quadrilateral space between four adjacent columns, and the beams connecting them, is a flat slab supported at its edges. It is therefore desirable to so reinforce the slab that the stresses will be met as they occur. If the center of the slab were supported by a single concrete beam 85 connecting to diagonally opposite columns, the reinforcement of that beam would usually consist of tension members placed in the bottom of the concrete forming that beam. If two such beams joined at the 90 center of the slab, the reinforcement would also be at the bottom of the beams, and irrespective of the width of the beams, would consist of parallel rods. The patent to Turner, No. 1,003,384 dated Sept. 12, 1911, 95 is an example of an extreme type of this "two-beam" construction, and in Fig. 13, that patent shows six reinforced concrete beams between four columns forming an entire floor slab, two of the beams extending 100 diagonally between columns and transmitting the stresses which occur between the side beams of the panel directly to the columns. In the present invention, the reinforcements serve to create a large number 105 of beams extending radially from the center of the panel to the side beams, and incidentally to the column, each in the form of a sector of a circle. As each radial beam is very narrow, having only a single reinforcing bar, the efficiency of this construction is 110 very high. A strong ring 6 of steel has a

series of rods 7 connected to it, which rods extend radially and are preferably equally spaced circumferentially. These rods are preferably of such length that they extend beyond the rods 4. As shown in Fig. 2, these rods may extend horizontally and then be bent upwardly at their ends. Each rod reinforces a beam which is an inverted cantaliver extending from the center of the slab, and the ring 6 unites all the beams in a solid whole. In order to further strengthen the entire construction, similar rings 8 may be embedded in the concrete near the plane of the upper face of the floor slab, and rods 9 may extend radially therefrom, and incline downwardly into the concrete of the floor. This reinforcement, combined with the concrete of the slab around the column, forms a cantaliver of great efficiency. The concrete of the floor slab may be of even thickness throughout, or it may be formed as shown in Fig. 2, where the lower portion 10 is of a mixture well designed to resist compression, and the portion 11, a light concrete made with cinder or other material. It may even be omitted entirely. The tensional stresses per unit of area in a slab are greatest at the center of a panel. With this construction, the amount of reinforcing material is greatest where the greatest stresses occur.

In Figs. 3, 4 and 5, the steel columns 15 carry the steel beams 16. The rings 17 at the center of the panels unite the inner ends 35 of the rods 18, whose outer ends may be formed into hooks 19 which engage the upper flanges of the beams 16. These rods 18 are shown straight in Fig. 4, but they may be horizontal as at 20 in Fig. 5, with 40 their ends 21 inclined upwardly so as to extend over the beams. The concrete 22 of the slabs is indicated in dotted lines and may be homogeneous or of two kinds as shown in Fig. 2. In fact, this concrete is 45 merely incidental to the invention, as it is well known in many forms and mixtures. These reinforcing members may be assembled at the factory, and secured together in bundles properly labeled for the respective 50 panels where they are to be placed. The rings will unite the inner ends of the rods while the outer ends may be held together with a binder of wire. The rods 7, 9, 18 and 20 and the rings 6, 8 and 17, may be 55 of material of any desired cross section or deformation. While it is preferred that all the rods shall radiate from the centers of the rings to which they are connected, it will be understood that a variance of the 60 direction may be permitted, as it may be desired to have the rods extend tangentially to the rings.

Fig. 6 shows a slightly modified form of a cantaliver reinforcement together with the 65 concrete and falsework. The boards 23 of

the column-molds and the boards 24 of the floor slab falsework may be of any desired construction and material and supported in any desired manner. The vertical rods 1 are adapted to reinforce the column 2, while the concrete floor 25 will be of proper thickness. A ring 26 is embedded in the concrete of the column and tension members in the form of rods 27 extend downwardly from the ring into the floor slab. In order to 70 support the ring in proper position until the concrete has set, the inner ends 28 of rods 27, after being wound around the ring, may extend in such a manner that they engage the boards 24 and thus support the 75 ring.

I claim—

1. A structure of reinforced concrete comprising a flat floor slab having supporting beams along its edges and a metallic reinforcement for the slab consisting of a ring positioned substantially central with reference to the supports for the slab and a series of rods connecting to said ring by having their inner ends wound around the 85 ring and extending radially therefrom to the edges of the slab.

2. A structure of reinforced concrete comprising a flat floor slab and supporting beams therefor along its edges, and a metallic reinforcement for said slab consisting of a ring positioned substantially central with reference to the supports for the slab and a series of rods connecting to said ring by having their inner ends wound around the 95 ring and extending radially therefrom to the 100 said supporting beams.

3. An article of manufacture consisting of a collapsible reinforcement for concrete floor panels and comprising a metal ring 105 and metal rods each connected to the ring at one end and free at the other end so that the rods may be folded together in the same manner as the ribs of an umbrella for convenience in shipping, and be spread out for 110 embedding in the concrete.

4. A structure of reinforced concrete comprising a flat floor slab and supporting beams therefor dividing the slab into panels, and a metallic reinforcement for each panel 115 consisting of a ring in the center of the panel and a series of rods connecting to said ring by having their inner ends wound around the ring and extending radially therefrom to said supporting beams, said 120 rods being substantially evenly spaced circumferentially.

5. In a concrete structure comprising columns and floor slabs, means to reinforce the floor slabs between the columns, and means 125 to reinforce the slabs immediately around the columns consisting of metal rings in said columns near the upper surface of the floor and a series of rods wound around said rings and extending radially into the floor slabs, 130

- some of the rods having short ends next to the ring extending downwardly and slightly outwardly so that they may rest on the false-work employed in erecting the floor to support the rings until the concrete sets. 5
6. In a structure of reinforced concrete comprising columns and a floor slab, means for reinforcing the slab comprising rings in the columns near the upper face of the slab 10 and other rings in the slabs near their lower face and spaced centrally of the columns, and a series of radially extending rods connecting to each of said rings and having their ends overlapping the ends of adjacent rods radiating from the columns. 15
7. In a structure of reinforced concrete comprising concrete columns and a concrete floor slab, reinforcing rods extending between the columns to form reinforced beams 20 dividing the slab into panels, metal rings in the columns and rods radiating therefrom, metal rings in the centers of said panels, and rods connecting to said rings and extending radially into said beams and having 25 their ends overlapping the ends of adjacent rods radiating from the columns.
8. In a structure of reinforced concrete comprising concrete columns and a concrete floor slab, reinforcing rods extending between the columns to form reinforced beams 30 dividing the slab into panels, metal rings in the centers of said panels, and rods connecting to said rings and extending radially
- into said beams, said rods being substantially equally spaced circumferentially of the ring. 35
9. In a structure of reinforced concrete comprising concrete columns and a concrete floor slab, an open frame work of radial rods at the top of each column extending into the floor slab, a means to connect the inner ends 40 of the rods, and an open frame work of radial rods at the bottom of the floor slab in each quadrilateral between four columns, and means to connect the inner ends of the rods. 45
10. In a structure of reinforced concrete, 4. comprising columns and a floor slab, rods extending between the columns in the concrete of the floor to form reinforced beams and dividing the slab into panels, vertical reinforcing rods in the columns, radially extending rods in the columns inclining downwardly into the slab, a ring to connect the inner ends of each group of rods, radially extending rods in each panel, and a ring connecting the inner ends of each group of 50 rods, the outer ends of each group of rods over-lapping the ends of the rods of the adjacent groups. 55
- In testimony whereof I have signed this specification in the presence of two subscribing witnesses. 60
